UNITED STATES PATENT OFFICE.

MILLARD FILLMORE WALKER, OF FLATONIA, TEXAS.

RAILWAY-SIGNAL.

SPECIFICATION forming part of Letters Patent No. 678,818, dated July 16, 1901.

Application filed October 20, 1900. Serial No. 33,776. (No model.)

To all whom it may concern:

Be it known that I, MILLARD FILLMORE WALKER, a citizen of the United States, residing at Flatonia, in the county of Fayette 5 and State of Texas, have invented a new and useful Railway-Signal, of which the following is a specification.

The invention relates to improvements in railway-signals.

10 The object of the present invention is to improve the construction of railway-signals and to provide a simple and comparatively inexpensive one adapted to utilize the light of a telegraph-office or other structure and 15 capable of housing and protecting the parts and of being readily operated for displaying either a white or colored light.

The invention consists in the construction and novel combination and arrangement of 20 parts hereinafter fully described, illustrated in the accompanying drawings, and pointed out in the claims hereto appended.

In the drawings, Figure 1 is a perspective view of a railway-signal constructed in accordance with this invention. Fig. 2 is a longitudinal sectional view. Fig. 3 is a horizontal sectional view. Fig. 4 is a transverse sectional view on line 4 4 of Fig. 2. Fig. 5 is a 25 detail perspective view of the cap of the outer end of the box or casing, illustrating the arrangement of the mirrors.

Like numerals of reference designate corresponding parts in all the figures of the drawings.

30 35 1 designates a box or casing designed to extend through the wall of a telegraph-office or other structure, with one end arranged within the structure and its other end on the exterior of the same in order that the light of the office may be utilized for illuminating night-signals. The box or casing, which is preferably rectangular in cross-section, as shown, 40 may be constructed of any suitable material and may be mounted in proper position above the track in any suitable manner, and it is provided at its inner end with an opening 2, and it has lateral openings 3 at opposite sides of its outer end. The box or casing is provided at the openings 2 and 3 with plano-con- 45 50 vex lenses, and a light 4 is designed to be interposed between the inner end of the box or casing and a reflector 5, which throws a light

through the end opening 2 into the box or casing. The lens 6, which is located at the inner end of the box or casing, has its convex face at its outer side, and the lenses 7 at the sides of the box or casing have their plane faces at the inner sides. The rays of light thrown into the box or casing by the reflector are reflected through the side openings 3 by 55 a pair of mirrors 8, mounted on the removable end or cap 9, which closes the outer end of the box or casing. The mirrors, which are arranged at right angles to each other, are each arranged at an angle of ninety degrees 60 to the plane of the outer face of the end or cap 9, and they are adapted to reflect the rays of light through the side lenses at right angles to the length of the box or casing. The cap or end piece 9 is provided with triangular top 70 and bottom pieces 10, forming supports for the mirrors, and the said cap or end piece is adapted to be readily removed to afford access to the interior of the box or casing for cleaning the mirrors or for cleaning or changing 75 the colored slides, hereinafter described.

The outer portion of the box or casing is provided at opposite sides with upper and lower ways 11 and 12, receiving colored slides 13, of glass or any other transparent material. 80 The slides are connected by a transverse bar 14 and are provided with suitable frames to receive the transparent material, and the said transverse bar is provided at its center with a perforated ear 15, which is detachably pivoted by a suitable fastening device to a reciprocating rod 15, and when it is desired to change the color of the slides the cross bar or piece 14 is detached from the rod; but instead of removing the slides in this manner any 85 other suitable provision may be made for changing the colored glass or other material. The longitudinal rod 15, which slides in a longitudinal groove 16, has its rear portion extended through a slot 17 of the bottom of 90 the box or casing, as clearly shown in Fig. 2 of the accompanying drawings. This exterior rear portion of the rod passes through a suitable guide 18 and has disposed on it a spiral spring 19, which is interposed between the 95 said guide 18 and a suitable stop 20 of the rod and adapted to maintain the signal in one position and to return it automatically to such position after it has been operated and is free

to move. The stop 20 may consist of a collar or flange, and the rear end 21 of the rod is bent at an angle and has a cord 22 or other flexible connection attached to it. This cord 5 extends forward over a pulley 23, which is mounted beneath the box or casing at one side of the reciprocating rod, and the said cord may extend from the said pulley to any desired point, and when pulled it is adapted 10 to reciprocate the rod against the action of the coiled spring for carrying the colored slides over the lenses for displaying a colored signal. The cord may be secured in any suitable manner for retaining the colored slides 15 at the apertures or openings of the sides of the box or casing, and when it is released the coiled spring will operate automatically to return the slides to their initial position.

It will be seen that the railway-signal is 20 exceedingly simple and inexpensive in construction, that it is positive and reliable in operation, and that the light of an office or the like may be utilized, thereby dispensing with a lamp or other illuminating means for 25 the signal. It will also be apparent that the parts are housed within the box or casing or arranged within the office or other structure, so that the signal is not affected by the weather, and that ready access may be had 30 to the interior of the box or casing for cleaning the parts or changing the slides.

What is claimed is—

1. A railway-signal comprising a casing provided at its inner end with an opening 35 and having side openings at its outer end, a removable cap covering the outer end of the casing and provided with mirrors arranged to reflect light through the side openings, said mirrors being mounted on and carried 40 by the said cap, colored slides adapted to cover and uncover the side openings, and means for operating the slide, substantially as described.

2. A railway-signal comprising a casing provided at its inner end with an opening 45 and having side openings at its outer end, a removable cap or cover fitted on the outer end of the casing and provided with triangular supports located at its inner face, the mirrors arranged at an angle and secured to the 50 triangular supports and carried by the removable cap or cover, and colored slides arranged to cover and uncover the side openings, substantially as described.

3. A railway-signal comprising a casing 55 provided at its inner end with an opening and having side openings at its outer end, said casing being provided at opposite sides with ways, colored slides mounted in the ways and provided with a connecting cross-piece, a reciprocating rod extending from the cross-piece through the bottom of the casing, a spring engaging the rod to hold the slides in one position, operating mechanism connected with the rod and adapted to reciprocate 60 the same to change the position of the slides, and mirrors arranged within the casing, substantially as described.

4. A railway-signal comprising a casing provided at its inner end with an opening 70 and having side openings at its outer end, colored slides arranged to cover the side openings, a cross-piece connecting the slides, a reciprocating rod extending from the cross-piece, a spring for holding the slides in one 75 position, and operating mechanism connected with and adapted to reciprocate the rods to change the position of the slides, substantially as described.

In testimony that I claim the foregoing as 80 my own I have hereto affixed my signature in the presence of two witnesses.

MILLARD FILLMORE WALKER.
